UNITED STATES PATENT OFFICE.

JOSEPH CHABOT, OF NORTH ATTLEBORO, MASSACHUSETTS, ASSIGNOR TO GEO. L. PAINE COMPANY, OF NORTH ATTLEBORO, MASSACHUSETTS, A CORPORATION OF RHODE ISLAND.

BELT-BUCKLE.

1,227,115.

Specification of Letters Patent. Patented May 22, 1917.

Application filed November 4, 1916. Serial No. 129,609.

To all whom it may concern:

Be it known that I, JOSEPH CHABOT, a citizen of the United States, residing at North Attleboro, in the county of Bristol and State of Massachusetts, have invented 5 a new and useful Improvement in Belt-Buckles, of which the following is a specification.

This invention relates to certain new and 10 useful improvements in belt buckles, and it has for its primary object to provide a buckle of simple and novel type which has means incorporated therein for permitting the clamping member to be manipulated so 15 as to allow of the belt end being easily inserted.

Further, the invention aims to provide a clamping device which can be easily and quickly manipulated, and which is also positively moved to position to allow of the 20 insertion of the belt.

Other and further objects will be later herein set forth and manifested in the course of the following description.

25 In the drawings—

Figure 1 is a front elevation of the invention.

Fig. 2 is a top plan view.

Fig. 3 is a rear elevation.

30 Fig. 4 is a section on the line 4—4 of Fig. 1, and

Fig. 5 is a similar view on the line 5—5 of Fig. 3.

In proceeding in accordance with the 35 present invention, a casing is employed which has a front wall 1 and side walls 2, each of the latter being provided with registering slots 3, through which a bar 4 is passed. Heads 5 are formed on the bar 4, 40 and enable the latter to be actuated in a manner hereinafter described from either one or both ends of the bar.

A clamping member 6 is secured 45 to the bar 4 and is formed with a struck-out jaw 7 adapted to bite into or grip the belt end B. Member 6 has right angular sides 8 through which the bar 4 is passed and one of these sides is engageable, at its edge with a cam 9 secured adjacent one of the side 50 walls 2 of the casing as depicted in Fig. 4 of the drawings.

An anchoring bar 10 is affixed to the casing to secure the other end C of the belt thereto, and a limiting bar 11 is also se-

cured to the side walls 2 of the casing to 55 restrict the out movement of the clamping member and to effect clamping of the latter.

The side 8 of the clamping member 6 adjacent to the cam 9 is formed somewhat rounded at 12, so that when the clamping 60 member is drawn toward the cam 9 it will ride up on the latter and thus cause the free or front end of the clamping member to rock or swing outwardly toward the bar 11, thus permitting the belt end B to 65 be easily slid into the casing, as shown in dotted lines in Fig. 2. Any tendency toward movement of the belt end C away from the casing will cause the inclined outer face of the clamping member to ride on 70 or against the bar 11, and thus force the jaw 7 into engagement with the belt end C, as will be apparent. For this latter purpose the clamping member 6 has an inclined disposition so that it will be wedged 75 between the bar 11, and casing front 1, as will be apparent from Fig. 4 of the drawings.

The jaw 7 is a part of the clamping member 6 and moves therewith so that the wedging action of the bar 11 will be at a point directly to the rear of the jaw to thus more effectively hold jaw 7 in position clamping the belt. The heads 5 allow the clamping member to be easily operated from either 80 or both ends of the bar 4 and the slots 3 in which the ends of the bar 4 ride and are guided assure easy and certain movement of the clamping member in a defined path.

The invention thus provides a simple 85 means for clamping the belt in a certain and positive manner and for also enabling the clamping member to be easily manipulated to receive the belt end for clamping.

Having thus described my invention, what 90 I claim as new and desire to secure by Letters Patent is—

1. A belt buckle including a casing formed with side walls provided with registering slots, a bar slidable in the slots and having 100 its ends headed, a clamp having side flanges through which the bar is passed, a cam fixed in the casing, one of the side flanges of the clamp being rounded to engage the cam whereby upon such engagement the free end 105 of the clamp will be automatically raised to allow of the insertion of a belt end between the clamp and the casing, said clamp hav-

ing an inclined disposition when in locking position, and a cross bar carried by the casing to engage the free end of the clamp to limit the outward movement thereof and to 5 wedge the clamp into clamping position, said clamp having a jaw struck-out therefrom and disposed adjacent the last named cross bar.

2. A belt buckle, including a casing, a 10 clamp, means to connect the clamp to the casing to allow of slidable and pivotal movement thereof, a fixed cam borne by the casing, means on the clamp to engage the cam and automatically rock the clamp upon sliding movement of the clamp in one direction, and means to engage the clamp to move same to belt clamping position upon movement of the clamp in the opposite direction.

3. In a belt buckle, a casing, a clamp, 20 means to connect the clamp at one end thereof to the casing so that the clamp may bodily slide and have oscillatory movement at its opposite end, means to force the clamp into belt clamping position upon sliding thereof in one direction, and means to oscillate said opposite end of the clamp to move same out of belt clamping position upon sliding of the clamp in the opposite direction.

4. In a belt buckle, a casing, a clamp, 30 means to connect one end of the clamp to the casing so that said end of the clamp is free of engagement with the belt and the opposite end may oscillate toward and away from the casing, means engageable with said 35 first named end of the clamp to move said oscillatory end of the clamp out of belt clamping position, and means to actuate the oscillatory end of the clamp to move same into belt clamping position.

5. A belt buckle including a casing, a 40 clamp, means to pivotally and slidably connect the clamp to the casing so as to cause same to have an inclined relation thereto, means to automatically rock the clamp so as 45 to move same completely out of belt clamping position upon movement of the clamp in one direction, and means engaging the inclined part of the clamp to wedge same to clamp the belt upon movement of the clamp 50 in the opposite direction.

In testimony whereof I have signed my name to this specification in the presence of two subscribing witnesses.

JOSEPH CHABOT.
